UNITED STATES PATENT OFFICE.

GEORGE EDWIN PERKINS, OF ATKINSON, ILLINOIS, ASSIGNOR OF ONE-FOURTH TO OSCAR D. MALONEY AND ONE-FOURTH TO PAUL D. RANSOM, OF ATKINSON, ILLINOIS, AND ONE-FOURTH TO ARTHUR BURRALL, OF ROCK ISLAND, ILLINOIS.

COMBINED MAIL-BAG CATCHER AND DELIVERER.

No. 853,472.

Specification of Letters Patent.

Patented May 14, 1907.

Application filed July 30, 1906. Serial No. 328,488.

To all whom it may concern:

Be it known that I, GEORGE EDWIN PERKINS, a citizen of the United States, residing at Atkinson, in the county of Henry and State of Illinois, have invented certain new and useful Improvements in a Combined Mail-Bag Catcher and Deliverer; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to combined mail bag catchers and deliverers, and has for its purpose to so construct and arrange the parts that there may be an exchange of mail bags between a moving train and a station with certainty and without danger to person or property and with the minimum of strain and wear on the exchanging devices and the parts to which they are attached; also to provide longer life to the parts and without breakage or liability to get out of working condition, and in which the parts will be simple of construction, and easy of application, and also in which the parts of the device attached to the car can be readily transferred or exchanged in position according to the direction in which the train is running; also to provide for delivering the mail sacks while resting upon the floor of the car, if it be so desired, without the necessity of actual suspension of the sacks from the delivery arm.

To the accomplishment of the foregoing and such other objects as may hereinafter appear, the invention consists in the features and in the arrangement of parts hereinafter described and then sought to be clearly defined by the claims, reference being had to the accompanying drawings forming a part hereof, and in which

Figure 1 is a side elevation of the station and car catching and delivery mechanism; Fig. 2 is a plan view of the same; Fig. 3 is a front view looking at the car door; Fig. 4 is a side sectional view of the delivery hook; Fig.

5 is a plan sectional view of same; and Fig. 6 is a side view of a modified form of hook.

The numeral 1 designates the doorway of a mail car to the sides of which are secured the brackets 2 designed to receive the cross rod or bar 3 which is provided at each end with a gravity pin 4 which normally will stand at right angles to the bar so as to prevent the bar from slipping out of the brackets, which pins when turned parallel with the rod will permit the rod to be moved longitudinally to remove it from the brackets for the purpose of reversing the position of the mail bag catcher fork. Upon this rod slides the mail catcher arm 5 having the fork 6 to receive the mail bag cable 7, and has the spring influenced catches 8 to prevent the cable from accidentally leaving the fork when received between its prongs. The fork fits in a slot 9 formed at the end of the arm and is held therein by a bolt or pin 10 so as to permit it to have a slight lateral play to accommodate it to any variations in the position of the bag suspending cable and to permit it to move slightly when it receives the cable.

The arm 5 has a sleeve 14 which encircles the rod 3 and is provided on opposite sides with antifriction rollers 15, one adjacent to each end, so as to enable the sleeve and its arm to slide freely on the rod as against the tendency of the sleeve to bind on the rod by reason of the force and direction of the impact given when the suspending cable of the bag deliverer at the station is grasped by the catcher on the car. The sleeve 14 has a handle 16 by which it may be turned to bring the catcher to a horizontal or projected position, and for holding it in that position it is provided with a lug 17 which will fit in a socket 18, with which each of the brackets 2 is formed, when the fork is shifted to its receiving position. A spring 19 is placed around the rod 3 at one side of the doorway so that the catcher fork will be cushioned when it is moved to that side after catching the bag. When moved from its projected position the catcher arm and fork drop to a position to bring the bag within the car door. The receiving fork is provided with a wind-

guard 20 which is slidable through the head of the bolt which secures the fork to its arm. This wind-guard has at one end a spring hook 21 which when the wind-guard is not in use 5 fits around the sleeve 14 so that the wind-guard will lie in its non-active position. When the receiving fork and the delivery arm are in their active positions, the wind-guard is projected outwardly so as to lie in 10 the plane of the suspended mail bag and serve to prevent the swaying of the mail-bag so that its cable will remain in position to be caught by the receiving fork of the station crane.

15 The delivery arm is designated by the numeral 22 which has a sleeve 23 fitting around a rod or post 24 whose lower end is angular in cross section and fits in one of two sockets 25 secured to opposite sides of the door frame 20 and is formed with a shoulder 26 upon which the sleeve of the delivery arm will rest, said shoulder and the meeting face of the sleeve being formed one with a notch or recess 27 and the other with a lug 28 to engage each 25 other for the purpose of holding the arm in its projected position when positioned to have a mail bag delivered therefrom. The upper portion of the rod or post 24 passes through a keeper 29 which aids in securely holding it 30 in an upright position. The rod or post is encircled by a spring 30 the lower end of which bears against the sleeve 23 of the delivery arm and its upper end against a collar or nut 31 which is adjustable by turning it 35 on a screw threaded portion 32 of the rod or post so as to regulate the tension of the spring. This tension regulator is for the purpose of enabling the delivery arm to resist the tendency of being accidentally swung 40 from position by any extraordinary force of wind currents. The spring also serves to permit a sufficient vertical movement of the delivery arm to disengage its locking means when the mail bag cable is grasped and 45 pulled by the station catcher crane so that the delivery arm may swing in toward the car door. When the arm is moved to a position parallel with the door it will be held or locked in that position by the lug 28 engaging 50 the notch 33 suitably positioned for the purpose. The socket and keeper for the delivery arm post permit the post and arm to be readily detached so as to transfer them to the corresponding socket and keeper at the other 55 side of the doorway when the car is running in the other direction.

The delivery arm 22 carries at its end a suitable hook for holding the cable by which the mail bag is suspended. In one form this 60 hook consists of the two jaws 34 which are spread apart by a suitable spring, which may be a coiled spring 35 interposed between the jaws, one of said jaws being pivotally secured by a bolt 36 so as to have a slight movement.

One jaw is formed with a depression 37 and 65 the other with a shoulder 38 to receive a ring 39 on the end of the suspension cable. The jaws are pressed one toward the other in putting on the ring, and the spring keeps the jaws opened or distended so as to firmly 70 clamp the ring from the inside. This forms a very secure hold on the ring and prevents the same from pulling off except under an oblique pull on the ring which is given from the cable when the latter is caught and pulled 75 by the bag catcher or receiving hook. When thus pulled the ring will turn slightly and press on the jaws so as to compress them and allow the ring and its cable to be pulled from the hook. Instead of such form of hook, the 80 form illustrated in Fig. 6 may be used in which the jaws 40 will be rigid and have an open mouth 41 with an eye 42 back of the same so that a knot formed on the end of the cable, instead of a ring, will bear against the 85 side of the eye so as to sustain the cable and its bag and yet permit the cable to be easily withdrawn through the open mouth of the hook. The shank of the hook is pivoted to the slotted end of the arm by bolt 11 so as to 90 have a slight lateral play which is restricted by its sides coming against the shoulders 12 of the slot in which it is pivoted, and a spring 13 may be provided to cushion the jaw and hold it in its normal position. 95

The station crane consists of an arm 43 extending laterally from a revoluble post 44 supported upon a base 45, the meeting faces of the post and base being formed one with recesses 46 and the other with lugs 47 which 100 serve to hold the revoluble post at the positions to which it may be turned as the overhanging arm may extend in the direction of the track, or otherwise. The overhanging arm 43 carries at its outer end a double catching or receiving fork 48 pivotally connected with the arm so as to have a slight lateral play and provided with a spring 49 similar to that shown in my patent No. 614756 of November 22, 1898 and for the same purpose. 105 It also carries at its end a delivery hook similar to that described for the delivery arm of the car. The hook and fork of the overhanging arm are attached to the end of a rod 50 which is slidable in the overhanging arm 110 and is under the influence of a spring 51 which cushions the hook and the fork by allowing the rod a slight longitudinal movement when the bag is caught from the car hook and the other bag is delivered to the car 115 fork, thus preventing any undue strain on the parts and permitting the easier catching and delivery of the bags. From the lower portion of the revoluble post there extends an arm 52 provided with a handle 53 by 120 which the post may be turned so as to bring its overhanging arm in the direction of the track. From the upper portion of the base 125

45 extends a bracket 54 which supports a bumper consisting of a rod or bolt 55 bolted or otherwise rigidly secured to the bracket and extending on opposite sides thereof and 5 which is encircled by springs 56 against which bear the caps 57 which are slideable on the rod or bolt. To the ends of extensions 58 projecting from the bracket are pivoted gravity latches 59, which in the form shown 10 consist of the depending weighted arms 60 having inclined ends 61. When the post is swung around the arm 52 strikes the bumper cap which is moved against the cushioning spring, and at the same time an incline 62 on the lower face or edge of the arm 52 presses against the inclined end of the gravity latch and passes over the same. The inclined end then bears against the outer side of the arm and locks the same in place so as to hold the 15 bag carrying arm in a position extending away from the tracks. The pressure of the bumper spring against the arm 52 presses the lower end of the latch inwardly toward the bracket and it strikes against a part of the bracket so as to limit its movement. The 20 action is the same in whichever direction the revolute post is turned. An opening 63 is formed in the arm 52 to receive the end of the bumping bolt or rod when the spring is compressed. An automatic lock is thus formed 25 for the revoluble post when it is turned from the impact and momentum arising from the engagement of the catching and delivering devices, and the spring bumper serves to 30 cushion the post in arresting its rotation.

It will be observed that the catcher and delivery arms on the car are so located that the lower portion of the doorway is left entirely 35 unobstructed. This enables the mail sacks 40 in the car to rest on the car floor in front of the door, if so desired, and by using a cable of sufficient length to reach from the sacks on the floor to the hook of the car delivery arm, the sacks will be pulled out of the car door 45 when the cable is grasped by the catching fork of the station crane. In this operation as the catching fork on the station crane pulls on the cable which connects the sacks on the car floor with the hook of the car 50 delivering arm it draws the delivering arm toward the car door at the same time that the station catching arm is moving away from the car, with the result that at the same time that the cable is drawn out of the delivery 55 arm hook the sacks are pulled out of the door and swung by the station crane to one side away from the car, and without the sacks being caught and held or pulled by the sides of the door frame, and without strain on the 60 car door delivery arm which is moved toward the door instead of away from it. This avoids the necessity of actually suspending the sacks from the delivery arm of the car, although that may be done if preferred. The

construction and application of the catching 65 and delivery devices on the car door frame is also such that either or both of said devices may be set for action and the door closed without interference of one with the other.

Having described my invention and set 70 forth its merits, what I claim is:

1. In a mail bag catcher and deliverer, an arm carrying a catcher-fork, a rod extending across a car doorway for carrying said arm, keepers for said rod to fit in, and pivoted 75 catches attached to the ends of said rod and adapted to extend at an angle to the rod to prevent its displacement from the keepers and to be moved parallel with the rod when the rod is to be withdrawn, substantially as 80 described.

2. In a mail bag catcher and deliverer, a supporting rod extending across a car doorway, and an arm carrying a catcher-fork and formed with a sleeve slideable on said rod, 85 said sleeve having anti-friction rolls adjacent to its ends and located to bear on opposite sides of the supporting rod, substantially as described.

3. In a mail bag catcher and deliverer, a 90 catcher-fork arm sustained from a support on a car, and a slideable wind-guard carried by said fork and adapted to be projected and retracted, substantially as described.

4. In a mail bag catcher and deliverer, a 95 delivery-arm post attached to a car, and a delivery arm formed with a sleeve rotatably mounted on said post, said sleeve and post being formed with interlocking devices for securing the arm in position and adapted to 100 be disengaged as the bag is snatched from the arm so that the arm may swing to its inactive position, substantially as described.

5. In a mail bag catcher and deliverer, a laterally swinging delivery arm supported on 105 a car, and means for regulating resistance offered by said arm against lateral movement, substantially as described.

6. In a mail bag catcher and deliverer, a delivery arm post attached to a car, a laterally swinging delivery arm rotatably mounted on said post, and means for regulating resistance to be offered by said arm against lateral movement, substantially as described. 110

7. In a mail bag catcher and deliverer, a 115 delivery-arm post attached to a car, a laterally swinging delivery arm rotatably mounted on said post, a spring acting on a part of said arm to offer resistance to lateral movement of the arm, and means for regulating the 120 tension of said spring, substantially as described.

8. In a mail bag catcher and deliverer, a delivery-arm post formed with an angular portion fitting in a correspondingly shaped 125 socket attached to a car, a portion of said post being threaded, a delivery-arm having a sleeve rotatably mounted on said post, a

- 4
- spring encircling the post at one end of said sleeve, and a threaded nut or collar fitting to the threaded portion of the post to regulate the tension of said spring, substantially as 5 described.
9. In a mail bag catcher and deliverer, a delivery arm provided with a cable suspension-hook connected to the arm to have a limited lateral movement relatively thereto, 10 said hook having a slotted end fitting within said arm, a bolt passing through said slot and supported by the arm, and a spring bearing against opposite sides of the hook for holding said hook in its normal position, substantially 15 as described.
10. In a mail bag catcher and deliverer, a delivery arm provided with a cable suspension-hook having jaws one movable relatively to the other, and a spring to hold the jaws 20 normally spread apart, substantially as described.
11. In a mail bag catcher and deliverer, a delivery arm provided with a cable suspension-hook having jaws one movable relatively to the other, one of said jaws being 25 formed with a depression on its outer face and the other with a shoulder, and a spring to hold the jaws normally spread apart, substantially as described.
12. In a mail bag catcher and deliverer, a crane comprising a base, a rotatable post thereon having an overhanging arm provided with mail bag catching and delivering devices, and an elastic bumper, against which a 30 part of the rotatable post strikes for cushioning the post in its rotation, substantially as described.
13. In a mail bag catcher and deliverer, a crane comprising a base, a rotatable post thereon having an overhanging arm carrying 35 mail bag catching and delivering devices, and an automatically acting lock for holding the
- post and its arm in position with the arm removed from its receiving and delivering position in either direction of rotation of the 45 post, substantially as described.
14. In a mail bag catcher and deliverer, a crane comprising a base, a rotatable post having an overhanging arm carrying mail bag catching and delivering devices, an arm 50 extending from the lower portion of the post, and a gravity catch to engage a part of said arm to hold the post with its overhanging arm in its withdrawn position, substantially as described.
15. In a mail bag catcher and deliverer, a crane comprising a base, a rotatable post having an overhanging arm carrying mail bag removing and delivering devices, an arm 55 extending from the lower portion of the post, a cushioned bumper for said extended arm to strike against, and a catch for engaging said arm to hold the post and its overhanging arm in their withdrawn position, substantially as described.
16. In a mail bag catcher and deliverer, a crane comprising a base, a rotatable post having an overhanging arm carrying mail bag receiving and delivering devices, an arm 60 extending from the lower portion of the post, a bracket supported by the base, a spring bumper supported by said bracket, and a gravity catch for engaging the arm extending from the post when it strikes the bumper and holding said post and its overhanging arm in 65 their withdrawn position, substantially as described.
17. In testimony whereof I affix my signature in presence of two witnesses.

GEORGE EDWIN PERKINS.
